J. HANDELAND.
POWER PROPELLED SLED.
APPLICATION FILED JAN. 18, 1915.

1,176,053.

Patented Mar. 21, 1916.

UNITED STATES PATENT OFFICE.

JOHN HANDELAND, OF TWO HARBORS, MINNESOTA.

POWER-PROPELLED SLED.

1,176,053.

Specification of Letters Patent. Patented Mar. 21, 1916.

Application filed January 18, 1915. Serial No. 2,779.

To all whom it may concern:

Be it known that I, JOHN HANDELAND, a citizen of the United States, residing at Two Harbors, in the county of Lake and State 5 of Minnesota, have invented certain new and useful Improvements in Power-Propelled Sleds; and I do hereby declare the following to be a full, clear, and exact description of the invention, such as will enable others skilled in the art to which it 10 pertains to make and use the same.

My invention relates to improvements in power propelled sleds; and, to this end, it consists of the novel devices and combinations 15 of devices hereinafter described and defined in the claim.

In the accompanying drawings, which illustrate the invention, like characters indicate like parts throughout the several views.

20 Referring to the drawings: Figure 1 is a side elevation of a bob-sled having the invention incorporated therein; Fig. 2 is a rear end elevation of the same; Fig. 3 is a plan view of one of the rear sled runners 25 removed from the sled body, on an enlarged scale; Fig. 4 is a longitudinal vertical section taken on the line $X^4 X^4$ of Fig. 3; and Fig. 5 is a transverse vertical section taken on the line $X^5 X^5$ of Fig. 4.

30 The numeral 1 indicates the body of a bob-sled, and the numerals 2 and 3 indicate, respectively, the front and rear runners of said bob-sled. Secured to the front end of the body 1 is a depending casting 4 to which 35 the front runners 2 are secured for common horizontal swinging movement and for independent vertical oscillatory movements. Any suitable steering device may be provided for steering the front runners 2 and 40 for the purpose of this case is not thought necessary to illustrate the same. Depending from the under side of the rear portion of the body 1 is a pair of brackets 5 to which 45 is secured a pair of axially alined outwardly projecting stub axles 6.

As shown, each of the rear runners 3 comprises a pair of laterally spaced duplicate members each having a pair of upwardly converging arms 7. To the upper ends of 50 the four arms of each runner 3 is rigidly secured a hub 8. These hubs 8 are loosely journaled, one on each of the axles 6, permitting free, independent vertical oscillatory movements of the runners 3. The members of each rear runner 3 are rigidly connected and held laterally spaced by a multi-

plicity of horizontal rods 9 that are laterally spaced longitudinally on said runners. Journaled on the rods 9 of the respective runners 3 are rollers 10 over which runs a 60 link belt 11 having road engaging teeth 12. As best shown in Fig. 5 the lower faces of the rollers 10 are set rigidly above the lower edges of the members of the runners 3 so that the belt 11 running thereover follows 65 the outline of the road engaging surfaces of the runner members. The depending edges of the members of the runners 3 also hold the link belts against edgewise movements and in position on the engaged rollers 10. 70 At the front and rear ends of each runner 3 are journaled respectively sprocket wheels 13 and 14 over which runs the respective belt 11. An idle guide sprocket wheel 15 is journaled to the front arm 7 of each runner 3 75 and under which wheel the respective belt 11 runs.

To cause the bob-sled to move forward the belts 11 are driven, in the direction of the arrow marked thereon in Fig. 4, by an explosive engine mounted on the body 1. This engine is indicated as an entirety by the numeral 16 and may be of any desired construction. The belts 11 are independently driven from the engine 16 by the following 80 connections, to-wit: Keyed to each end of the engine crank shaft is a sprocket wheel 17 and loosely journaled on each stub axle 6 is a relatively large sprocket wheel 18 and a relatively small sprocket wheel 19, connected for common rotation. The sprocket wheels 17 and 18 are alined and a sprocket chain 20 runs thereover. The sprocket wheel 19 is alined with a sprocket wheel 21 on the shaft of the respective wheel 13 and 90 over which sprocket wheels 19 and 21 runs a link chain 22. In actual practice clutches, not shown, will be provided for rendering either of the driving connections from the engine to the road engaging belts 11 operative and inoperative, at will. 95

From the foregoing description, it is evident that during the forward movement of the bob-sled the weight of the load on the runners 3, together with the teeth 12, will 105 securely hold the underlying sections of the link belts 11 on the road bed and against slippage. Under the forward drawing action of the upper runs of the belts 11 over the sprockets 14 the runners 3 are caused to 110 slide forward over the underlying portions of the belts 11.

What I claim is:

A sled runner comprising a pair of laterally spaced runner members rigidly connected by a plurality of rods, a pair of sprocket whels journaled on certain of said rods, anti-friction rollers journaled on other of said rods, each runner member having a pair of upwardly converging arms, a common hub rigidly secured to the upper ends 10 of said arms and connecting the arms of the

two runner members, a link belt arranged to run over said sprocket wheels and rollers and having road engaging teeth, and means for driving one of said sprocket wheels.

In testimony whereof I affix my signature 15 in presence of two witnesses.

JOHN HANDELAND.

Witnesses:

J. GILBERT JELLE,
J. S. JOHNSON.
